HASP

William O. Kirkpatrick, Milwaukee, Wis., assignor to E. R. Wagner Manufacturing Company, Milwaukee, Wis., a corporation of Wisconsin

Application September 12, 1950, Serial No. 184,402

5 Claims. (Cl. 292—209)

1

This invention relates to improvements in hasps or clasps, especially designed and adapted for use with suitcases, trunks, boxes, and other similar receptacles.

In hasps of this character simplicity of construction, lightness in weight, and low manufacturing cost are desirable so long as appearance and durability are not sacrificed.

It is an object of this invention, therefore, to provide a hasp which may be inexpensively manufactured, is attractive in appearance, durable, and easily applied to the receptacle.

This object is obtained by providing a hasp plate, portions of the top wall of which are formed downwardly to provide penetrating prongs as well as simple and effective holding means for the hasp spring. An over-center acting hasp spring snaps into place on the under side of the hasp plate and its legs straddle the penetrating prongs, one of which has notches with which such legs engage to hold the spring in place and provide a fulcrum therefor. A hasp is pivoted to said plate and has a camming lug against which said hasp spring rests. This construction is inexpensive because: the plate penetrating prong and spring holder are made in one operation from a single sheet of metal; the hasp assembles easily to the plate; and a single operation puts the spring in place so that it can operate the hasp as well as hold it assembled.

The novel features which are considered characteristic of the invention are set forth with particularity in the appended claims. The invention itself, however, both as to its organization and its method of operation, together with additional objects and advantages thereof, will best be understood from the following description of a specific embodiment when read in connection with the accompanying drawings, in which:

Fig. 1 is a top plan view showing the hasp constructed in accordance with the present invention, the hasp being in the closed or latched position;

Fig. 2 is a sectional view taken on line 2—2 of Fig. 1;

Fig. 3 is a bottom plan view of the hasp viewed in Fig. 1;

Fig. 4 is a sectional view taken on line 4—4 of Fig. 1;

Fig. 5 is a sectional view taken on line 5—5 of Fig. 1;

Fig. 6 is a fragmentary plan view of the approximate layout of the penetrating prong development;

Fig. 7 is a fragmentary sectional view showing

2

the relation of the hasp and hasp spring when the hasp is partly open; and

Fig. 8 is a fragmentary sectional view showing the relation of the hasp and hasp spring when the hasp is fully open.

A hasp of the general character illustrated in the drawings is disclosed in the patent to Berthold R. Thiele 2,314,180 owned by the assignee hereof. Reference should be had to such patent for the details of construction of such of the parts herein mentioned which are of similar design.

The hasp or clasp comprises two principal parts. One of these, the keeper 10, is mounted on one section of the receptacle and the other, the hasp 14, is mounted on another section of the receptacle by means of a hasp plate 12. As the sections of the receptacle are brought together the hasp and the keeper come into alignment and interlocking engagement to hold such sections together.

The keeper 10 is similar to that described in the patent and has the usual boss 11 and toe 13. The boss 11 is engaged by the hasp 14 and the toe 13 alines the keeper with the hasp plate in the closed position. The hasp 14 is pivoted to a hasp plate 12 and held in such pivotal relationship by a hasp spring 40 having an over-center action to urge the hasp 14 into keeper-locking position or into fully open position.

One of the features of the hasp plate 12 is that the top 16 has part of its central portion cut out as shown in Fig. 6 leaving sections thereof having the shapes of penetrating prongs indicated at 22 and 24. These sections are bent downwardly from the plane of the top 16 to form the penetrating prongs by which the hasp plate 12 is secured to a receptacle. The prong 22, adjacent its juncture with the top 16, has a pair of spaced notches 26 adapted to receive and hold the legs 40 of the hasp spring 40 and thereby provide a fulcrum for such spring. Near the prong 24, the top 16 is displaced upwardly to provide transversely alined bearing sockets 28 adapted to cooperate with trunnions 30 on the hasp 14. In order to strengthen the hasp plate 12 and to space the top 16 from the surface of the receptacle, the plate is provided with a marginal depending flange 18. The height of the flange 18 is sufficient to provide adequate space for the operation of the hasp 14 and hasp spring 40 without interfering with the receptacle.

The hasp 14 has a substantially imperforate body provided with integrally formed trunnions 30 at one end. These trunnions are shaped to nest within the bearing sockets 28 to form pivotal

association between the hasp 14 and the hasp plate 12. Adjacent the trunnions the hasp 14 has a camming lug 32 which projects downwardly and rearwardly with respect to the body of the hasp 14 to cooperatively engage the legs of the hasp spring 40. As is shown in Fig. 3 the lug 32 may be cut away, as indicated at 34, to provide clearance for the penetrating prong 24 when the hasp 14 is in the locked position of Fig. 2. The hasp 14 is provided with a customary finger-piece 36 by which it may be manually lifted from locked position or by which it may be temporarily cammed over the boss 11 as the keeper 18 and hasp plate 12 are brought together.

One of the novel characteristics of the hasp 14 resides in the provision of a boss-locking edge 38. To form such edge the substantially imperforate body of the hasp has a small section cut therefrom at the juncture of the body and the finger-piece. The edge thus formed is relatively sharp and engages the side of the boss 11 with enough friction to prevent the hasp 14 from being accidentally unlocked. Thus the appearance of the hasp created by the imperforate body thereof is not affected and still the advantage of a good frictional grip between hasp and keeper is attained.

Another feature of this invention is the manner in which the hasp spring 40 is secured to the hasp plate 12 to operatively engage the camming lug 32 and hold the hasp 14 in pivotal association with such plate. The spring 40 is made of tempered spring wire formed in a general U shape having legs connected by a bridge portion. The legs of the spring 40 straddle both of the penetrating prongs 22 and 24 while the bridge rests against the under side of the top 16 between the marginal flange 18 and a small depending projection 42. The legs are inherently sprung inwardly enough so that they are slightly spread apart by the edges of prong 22 as the spring is forced upwardly thereof. Hence the legs snap into the notches 26 and are held therein with sufficient force to prevent the spring from being dislodged under normal operating conditions. The spring is held against movement longitudinally of the plate 12 by the engagement of the bridge by the flange 18 and projection 42. The legs are bent upwardly as indicated in Fig. 2 so that when the bridge rests against the top 16 and the intermediate parts of the legs are engaged in the notches 26 the end portions of the legs will be resiliently urged upwardly against the camming lug 32 with sufficient force to hold the trunnions 32 in pivotal relationship with the bearing sockets 28 and urge the hasp 14 to either locked or unlocked position.

Although only one embodiment of the invention is shown and described herein, it will be

understood that this application is intended to cover such changes or modifications as come within the spirit of the invention or scope of the following claims.

5 I claim:

1. A hasp comprising a hasp plate having a top with an opening therein, a spring holding member depending from an edge of said opening and having notches in the opposite edges thereof, a hasp pivoted to said plate and having a portion extending through said opening to provide a camming lug below said top, and a spring having spaced legs which straddle said member and are inherently biased into said notches to form a fulcrum connection between said member and spring whereby said spring is held in place by said member with its legs in operative engagement with said lug.
2. A hasp as claimed in claim 1 in which said spring has a bridge and said plate has a downward projection engageable with said bridge to aid in holding said spring in place.
3. A hasp as claimed in claim 1 in which said holding member extends below said notches and has its lower end pointed whereby it functions also as a fastening prong.
4. In a hasp, a hasp plate having a top with an opening therein spaced from the sides thereof, penetrating prongs depending from said top at opposite edges of said opening, a hasp pivotally related with said top and extending over said opening, said hasp having a portion extending within said opening to provide a camming lug, a spring having a bridge and legs, said legs straddling said prongs, and notches in the opposite edges of one of said prongs into which said legs are spring-biased to provide one fulcrum point therefor, said bridge being in contact with said top to provide a second fulcrum for said legs, the free ends of said legs being in resilient engagement with said camming lug whereby said hasp is urged to either open position or locked position and maintained in pivotal relationship with said top.
5. A hasp as claimed in claim 4 in which said top has a marginal flange and a downward projection spaced therefrom between which said bridge is engaged to hold said spring in proper place.

50 WILLIAM O. KIRKPATRICK.
